UNITED STATES PATENT OFFICE

2,417,303

FAN GEAR ASSEMBLY

Richard H. Jordan, Mansfield, Ohio, assignor to
Dominion Electrical Manufacturing, Inc., a
corporation of Ohio

Application June 20, 1945, Serial No. 600,571

10 Claims. (Cl. 230—264)

1
My invention relates to an oscillating mechanism for an electric fan and in particular to the housing for the working parts of that oscillating mechanism.

It is an object of my invention to provide an improved oscillating mechanism for an electric fan in which the working parts are entirely within the housing.

Another object of my invention is the provision of an oscillating mechanism including an axle in which the housing has internal slot means for holding the axle.

Another object of my invention is the provision of an oscillating mechanism in which the gears may be mounted on the axle and the axle then inserted from the top of the housing and into slots on the inside of the mechanism housing.

A further object of my invention is to provide an oscillating mechanism for an electric fan which is sturdy in construction and easy to assemble.

A still further object of my invention is to provide an improved housing for the working parts of an oscillating mechanism.

Other objects and a fuller understanding of my invention may be had by referring to the following description and claims taken in conjunction with the accompanying drawings, in which:

Figure 1 is a side elevational view of a fan embodying my oscillating mechanism;

Figure 2 is an enlarged side view, being shown in cross-section, of my oscillating mechanism, certain parts being omitted for clarity;

Figure 3 is a cross-sectional view of my invention taken along the line 3—3 of Figure 2, certain parts being omitted for clarity; and

Figure 4 is a cross-sectional view taken along the line 4—4 of Figure 3.

With reference to my drawings, and in particular to Figure 1, the reference character 10 represents a fan motor supported by the fan base 11 to rotate the fan blades 12. An oscillating mechanism 13 may be operated by the rotor shaft 14 to oscillate the fan with respect to the fan base. The oscillation of the fan disperses the air currents produced by the fan blades 12.

The fan motor 10 which rotates the fan blades 12 includes field lamination 16 and rotor lamination 17, which are carried by the rotor shaft 14. The motor may be pivotally supported upon an adjustable support arm 18 which is a part of the fan base 11. This adjustable support arm 18 may be pivotally mounted on the pivot rod 19 between the pivot mounting members 21 extending upwardly from the base 11. A set

2
screw 20 threaded into the pivot mounting members 21 and engaging the support arm 18 may be employed to lock the adjustable support arm in the desired position. The fan motor 10 may be oscillatively supported above the support arm 18 by the support shaft 22. It is understood that other suitable means may be employed to mount the fan motor on a fan base.

As illustrated in Figures 2 and 3, my oscillating mechanism 13 comprises primarily a gear box housing 25, a transmitting gear 26, and a revolute shaft 27 which carries the cam lever 28. The transmitting gear 26 drivingly connects the rotor shaft 14 to the revolute shaft 27. The cam lever 28 is fastened on one end to the revolute shaft 27 and on the other end to a link 29 which is also fastened to the base 11. The rotor shaft 14 revolves the revolute shaft 27 to oscillate the fan by means of the cam lever 28 and the link 29.

The gear box housing 25, as used in my oscillating mechanism 13, has a bottom 34, side walls 35, and a cover or top 36. It is noted that the housing completely encloses the working parts of oscillating mechanism 13.

25 In actual practice, the bottom and side walls of my gear box housing may be cast as a single unit or they may be constructed by other suitable means. The bottom 34 has a tubular shaped member 41 extending downwardly therefrom for supporting the revolute or cam driving shaft 27. This tubular shaped member 41 may be cast with the bottom 34 or it may be fastened by other suitable means, such for example welding, to the bottom 34.

30 The tubular shaped member 41 may serve as a bearing for the cam driving shaft 27. The side wall 35 includes a mounting wall 37 and supporting wall portions 43 and 44. The mounting wall 37 has a mounting bracket 38 which extends outwardly from the sides of the oscillating mechanism to engage the field lamination 16 of the motor 10. A mounting bolt 39 extends through openings in the mounting bracket 38 and through the field lamination 16, thus holding the oscillating mechanism 13 on the motor 10. It is understood that other suitable means may be employed to fasten the oscillating mechanism 13 to the motor 10.

35 The rotor shaft 14, which extends through an opening in the mounting wall and into the gear box housing 25, may be mounted in a bearing 60. I have employed a bearing support plate 61, which may be fastened by screws 62 to the mounting wall 37 for holding the bearing in the opening in the mounting wall portion 37 of the side wall 35.

A felt pad 63 may be placed about the bearing 60 and between the bearing support plate 61 and the mounting wall 37. Although I have used this particular bearing for my rotor shaft, it is understood that any suitable style of bearing may be employed.

The supporting wall portion 43 of the side wall 35 extends from one end of the mounting wall portion 37 and substantially perpendicular to the mounting wall portion 37. A supporting wall portion 44, which is similar to the wall portion 43, extends substantially parallel to the wall portion 43 and from the opposite end of the wall portion 37. These supporting wall portions 43 and 44 thus form the opposite walls of the gear box housing 25 and support the transmitting gear 26. In my description, I will describe the supporting wall portion 44. It is understood that the supporting wall portion 43 has the same respective parts as the wall portion 44, and that the respective parts of these two wall portions 43 and 44 are substantially aligned with each other.

The supporting wall portion 44 has an internal surface 45 which is on the inside wall of the gear box housing 25, and a top end surface 46 against which the cover or top 36 of the gear box housing is held. A substantially T shaped slot 47 extends from the top end surface 46 toward the bottom 34 and ends in a substantially semi-circular bearing surface 48. The substantially T shaped slot 47 opens on the internal surface 45 and also on the end surface 46. Although I have used a substantially T shaped slot, it is understood that slots of other designs may be employed with which the same results may be obtained. The substantially T shaped slot includes a back slot portion 51 and a front slot portion 52. The back slot portion 51, which is furthest from the internal surface 45, is wider than the front slot portion 52 which opens on the internal surface 45. The side of the back slot portion 51, which is closest the internal surface 45, defines an inside slot surface 49, formed by the flange 50, and an inside slot surface 52 formed by the flange 54. The flange 54 is larger than the flange 50, thus making the space between the flanges 50 and 54 less than the diameter of the transmitting gear axle 72. The transmitting gear 26 is supported between the wall portions 43 and 44 by holding the transmitting gear axle 72 on the slot bearing surfaces 48. The end of the axle which is inserted in the substantially T shaped slot 47 has a flat portion on the rounded surface thereof, which engages the flange 54 to prevent rotation of the transmitting gear axle 72. The transmitting gear thus revolves on the axle inserted instead of the axle revolving on the slot bearing surface.

Lips or flanges 55, which are located at the outside top end of the side wall 33, provide means for fastening the cover thereto. These flanges 55 are located on the supporting wall portions 44 and 43 and extend outwardly from the top end surface thereof. The cover or top 36 may be stamped from sheet steel and has flanges 56 positioned for alignment with the lips or flanges 55. After the parts have been placed in the gear box housing 25, the flanges 56 on the cover may be pressed around the lip or flange 55 on the supporting wall portion to fasten the cover to the gear box housing 25. The cover has an opening 57 which is in alignment with the tube shaped bearing 41 on the bottom. The revoluble or cam driving shaft 27 extends upwardly through this opening 57. I have chosen this type

of cover because of its practicability and simplicity to manufacture, but it is understood that other types of covers and means for fastening these covers may be employed.

The transmitting gear 26, which drivingly connects the cam driving shaft 27 to the rotor shaft 14 of the fan motor 10, includes a gear 70 and a worm gear 71. The gear 70 and the worm gear 71 are fastened together and are revolvably mounted on the axle 72. The axle 72 extends between the supporting wall portions 43 and 44 and is supported by the T shaped slots 47. Spacer washers 73 may be used to prevent the gear 70 and the worm gear 71 from rubbing the internal wall surfaces 45. In assembling the oscillating mechanism 13, the gears 70 and 71 may be mounted on the axle 72, which may then be dropped into the T shaped slots 47. Lugs 74 may then be inserted into the slots and between the axle 72 and the cover 36 to hold the axle 72 against the bearing surface 48. The gear 70 drivingly engages the worm 75 on the end of the rotor shaft 14, which extends into the gear box housing 25. These gears may be constructed from metal or other suitable materials which are machinable.

The revoluble or cam driving shaft 27 includes a lower shaft member 80, a gear 81, and an upper shaft member 82. The cam lever 28, which cooperates with the link 29 to oscillate the fan, is fastened to the external end portion 86 of the lower shaft member 80. The other inner end of the lower shaft member 80, which is within the housing 25, has a shoulder 84 and a threaded extension 85, extending outwardly from the shoulder 84. The gear 81 is floatingly mounted on the shoulder 84 and about the threaded extension 85. The upper shaft member has a threaded hole 88 for engaging the threaded extension 85 on the lower end thereof, and a knob 89 on the upper end thereof. I have placed a washer or collar 90 about the threaded extension 85 and between the gear 81 and the upper shaft member 82. This gear 81 is drivingly engaged to the worm gear 71. When the upper shaft member 82 is tightened onto the lower shaft member 80, thus frictionally engaging the gear 81 to the lower shaft member 80, the revoluble or cam driving shaft 27 is revolved by the gear. This frictionally engaging the gear 81 with the shoulder 84 to rotate the revoluble shaft 27 provides clutch means for the oscillating mechanism 13, whereby the fan may be made to oscillate at any desired time.

The rotor shaft continually turns the transmitting gear 26, which in turn continually turns the gear 81. When the operator wishes to oscillate the fan, he simply tightens the clutch by turning the knob 89 to cause the gear 81 to frictionally drive the cam driving shaft 27.

Although I have described my invention with a certain degree of particularity in its preferred form, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. In a housing for an oscillating mechanism having an axle, a first wall portion having an internal surface and a top end surface, a second wall portion substantially parallel to the first wall portion and having an internal surface and a top

end surface, said internal surface of the first wall portion facing the said internal surface of the second wall portion, said first wall portion having slot means opening on the said internal surface and the said end surface and terminating in a bearing surface, said second wall portion having slot means opening on the said internal surface and top end surface and terminating in a bearing surface, said slot means in the first wall portion and the said slot means in the second wall portion being aligned whereby the axle may be inserted in the slot means, an insertable member freely insertable in said slot means for holding the axle in the slot means and against the bearing surfaces, and a cover engaging said end surface to hold the insertable member in the said slot means.

2. In a housing for an oscillating mechanism having an axle, a first wall portion having an internal surface and a top end surface, a second wall portion substantially parallel to the first wall portion and having an internal surface and a top end surface, said internal surface of the first wall portion facing the said internal surface of the second wall portion, said first wall portion having slot means opening on the said internal surface and the said end surface and terminating in a substantially semicircular bearing surface, said second wall portion having slot means opening on the said internal surface and top end surface and terminating in a substantially semicircular bearing surface, said slot means in the first wall portion and the said slot means in the second wall portion being aligned whereby the axle may be inserted in the slot means, an insertable member freely insertable in said slot means for holding the axle in the slot means and against the substantially semicircular bearing surfaces, and a cover engaging said end surface to hold the insertable member in the said slot means.

3. In an oscillating mechanism having an axle, housing means having a first and a second wall portion, said first and second wall portions each having slot means with a portion of the slot means defining bearing surface, said bearing surface in the first wall portion being aligned with the said bearing surface in the second wall portion, means cooperating with the slot means for holding the axle against the bearing surface, said wall portion and said axle having cooperating means for preventing turning of said axle relative to said housing.

4. In an oscillating mechanism having an axle, housing means having a first and a second wall portion, said first and said second wall portions each having T-shaped slot means therein with a portion of the slot means defining a substantially semicircular bearing surface, said T-shaped slot means thereby defining flange means extending along said slot means and from said bearing surface, said slot means including a first portion disposed between said flange means and a second portion disposed behind said flange means, said bearing surface in the first wall portion being aligned with the said bearing surface in the second wall portion whereby said axle may be inserted into said slot means, and means insertable in said second slot portion and behind said flange means for cooperating with said slot means for holding the axle against the said bearing surfaces.

5. In an oscillating mechanism for oscillating an electric fan including a rotor shaft and a fan base, a gear box housing having a bottom, a side wall and a cover, a gear and a worm integral

with each other and disposed substantially at right angles to the said rotor shaft, said gear being drivingly connected to the said rotor shaft, an axle extending through the said gear and the said worm for revolvably supporting the same, said gear and said worm being free to rotate on said axle, said side wall being integral with the said bottom and having a top edge, said side wall having a first wall portion with mounting means for mounting the said oscillating mechanism and with an opening through which an end of the said rotor shaft extends into the said housing, said side wall having a second and a third wall portion oppositely disposed and each substantially at right angles to the said first wall portion, said second and said third wall portion each having slot means with the slot means in each of the wall portions facing each other and being aligned to receive the opposite ends of the said axle, said slot means opening on the said top edge of the wall and terminating in a bearing end surface near the base for supporting the said axle, means for holding the said axle against the curved end surface and in the said recess, said side wall having fastening means on the top edge for the fastening of the cover thereto, said cover and said bottom being provided with openings therethrough and having a shaft journaled therein with the shaft at substantially right angles to the said axle, and with each end of the said shaft extending outwardly beyond the said housing, a lever on one end of the said shaft, a link for connecting the said lever and the said fan base, a gear drivingly connected to the said worm and mounted upon the said shaft, a collar on the said shaft upon which the said gear may ride, and means revolvble on the other end of the said shaft and operable to clamp the said gear against the said collar for drivingly connecting the same to the said shaft whereby revolving the shaft oscillates the fan with respect to the fan base.

6. In an oscillating mechanism for an electric fan having a fan base and revolvble shaft, a housing having a top cover, a bottom portion, and side wall with an opening in said side wall through which the said revolvble shaft extends into said housing, transmitting gear means including an axle revolvably supported within the said housing and drivingly engaging the said revolvble shaft, said axle being supported at substantially right angles to the said revolvble shaft, said side wall having slot means on oppositely disposed sides of the said housing and facing each other with one end of the slot means opening at the top of the housing for receiving the ends of the said axle, spacer member for insertion into the said slot means between the said axle and the said cover to prevent the said axle from moving towards the said cover, said cover and said bottom portion having aligned openings with shaft means revolvably mounted therein and extending outwardly therefrom, said shaft means being substantially at right angles to said axle, cam means fastened to one end of the said shaft means and connected to the said fan base, said shaft having driving gear means engaging the said transmitting gear means with clutch means within the shaft means for drivingly engaging the shaft means with the said driving gear means, and means for operating the clutch means whereby, when the shaft means is drivingly engaged with the said transmitting gear means, the fan is oscillated with respect to the fan base.

7. In an oscillating mechanism for a fan, said oscillating mechanism having an axle, a gear box housing having a side wall, said side wall having a first wall portion with an opening therethrough and with mounting means associated therewith, said side wall having a second wall portion extending from one end of the said first wall portion, and said side wall having a third wall portion substantially parallel to the said second wall portion and extending from the opposite end of the said first wall portion, said second and third wall portions each having an inside surface and a top end surface with the said inside surfaces facing each other, the said second and the said third wall portions each having slot means opening on the said inside surfaces and extending from the top end surface thereof and terminating in a bearing surface, the said slot means in the said second and third wall portions being substantially in alignment with each other for receiving said axle said slot means and said axle having cooperating means for preventing turning of said axle in said slot means.

8. In an oscillating mechanism for a fan, said oscillating mechanism having an axle, a gear box housing having a side wall, said side wall having a first wall portion with an opening therethrough and with mounting means associated therewith, said side wall having a second wall portion extending from one end of the said first wall portion, and said side wall having a third wall portion substantially parallel to the said second wall portion and extending from the opposite end of the said first wall portion, said second and third wall portions each having an inside surface and a top end surface with the said inside surfaces facing each other, the said second and the said third wall portions having slots of substantially T shaped cross-section opening on the said inside surfaces and extending from the top end surface thereof and terminating in a substantially semicircular bearing surface, the said slots of substantially T shaped cross-section in the said second and third wall portions being substantially in alignment with each other for receiving said axle, said T shaped slot means thereby defining flange means extending along said slot means and from said bearing surface, said slot means including a first portion disposed between said flange means and a second portion disposed behind said flange means, and means insertable in said second slot portion and behind said flange means for cooperating with said slot means for holding said axle therein and against said bearing surfaces.

9. In an oscillating mechanism having an axle, housing means having a first and a second wall portion, said first and second wall portions each having slot means with a portion of the slot

means defining bearing surface, said bearing surface in the first wall portion being substantially aligned with the said bearing surface in the second wall portion, means cooperating with the slot means for holding the axle against the bearing surface when the axle is inserted in the slot means, said slot means and said axle having cooperating means for preventing rotation of said axle in said slot means.

10. In an oscillating mechanism for an electric fan having a fan base and removable shaft, a housing having a top cover, a bottom portion, and side wall with an opening in said side wall through which the said revoluble shaft extends into said housing, transmitting gear means including an axle revolubly supported within the said housing and drivingly engaging the said revoluble shaft, said axle being supported at substantially right angles to the said revoluble shaft, said side wall having slot means on oppositely disposed sides of the said housing and facing each other with one end of the slot means opening at the top of the housing for receiving the ends of the said axle, said slot means and said axle having cooperating means for preventing rotation of said axle in said slot means, spacer member for insertion into the said slot means between the said axle and the said cover to prevent the said axle from moving towards the said cover, said cover and said bottom portion having aligned openings with shaft means revolubly mounted therein and extending outwardly therefrom, said shaft means being substantially at right angles to said axle, cam means fastened to one end of the said shaft means and connected to the said fan base, said shaft having driving gear means engaging the said transmitting gear means with clutch means within the shaft means for drivingly engaging the shaft means with the said driving gear means, and means for operating the clutch means whereby, when the shaft means is drivably engaged with the said transmitting gear means, the fan is oscillated with respect to the fan base.
